US00D710843S

(12) **United States Design Patent**
Akana et al.

(10) **Patent No.:** US D710,843 S
(45) **Date of Patent:** ** Aug. 12, 2014

(54) **ELECTRONIC DEVICE**

(75) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/432,436**

(22) Filed: **Sep. 14, 2012**

Related U.S. Application Data

(60) Continuation of application No. 29/379,707, filed on Nov. 23, 2010, now Pat. No. Des. 672,343, which is a (Continued)

(51) **LOC (10) Cl.** **14-02**

Primary Examiner — Barbara Fox*(74) Attorney, Agent, or Firm* — Sterne, Kessler, Goldstein & Fox P.L.L.C.**CLAIM**

The ornamental design for an electronic device, as shown and described.

DESCRIPTION

FIG. 1 is a bottom front perspective view of an electronic device showing our new design;

FIG. 2 is a top front perspective view thereof;

FIG. 3 is a top rear perspective view thereof;

FIG. 4 is a bottom rear perspective view thereof;

FIG. 5 is a front view thereof;

FIG. 6 is a rear view thereof;

FIG. 7 is a top view thereof;

FIG. 8 is a bottom view thereof;

FIG. 9 is a left side view thereof; and,

FIG. 10 is a right side view thereof.

The shade lines in the Figures show contour and not surface ornamentation.

The broken lines in the figures show portions of the electronic device which form no part of the claimed design.

1 Claim, 8 Drawing Sheets## Related U.S. Application Data

division of application No. 29/363,172, filed on Jun. 5, 2010, now Pat. No. Des. 633,493, and a continuation of application No. 29/360,036, filed on Apr. 19, 2010, now Pat. No. Des. 627,778, said application No. 29/363,172 is a continuation of application No. 29/360,110, filed on Apr. 20, 2010, now Pat. No. Des. 633,908, which is a continuation of application No. 29/360,036.
